UNITED STATES PATENT OFFICE.

RUDOLPH F. KLOPP, OF MASON, MICHIGAN.

SAD-IRON.

SPECIFICATION forming part of Letters Patent No. 366,670, dated July 19, 1887.

Application filed August 20, 1886. Serial No. 211,415. (No model.)

To all whom it may concern:

Be it known that I, RUDOLPH F. KLOPP, of Mason, in the county of Ingham and State of Michigan, have invented new and useful Improvements in Sad-Irons; and I do hereby declare that the following is a full, clear, and exact description thereof, reference being had to the accompanying drawings, which form a part of this specification.

This invention relates to new and useful improvements in sad-irons; and it consists in the peculiar construction and combination of the parts, all as more fully hereinafter described, and set forth in the claims.

In the drawings which accompany this specification, Figure 1 is a vertical central longitudinal section through a sad iron of my improved construction. Fig. 2 is an end view thereof. Fig. 3 is a cross-section on the line xx in Fig. 1. Fig. 4 is a detached perspective view of the chimney-cap.

A is the hollow body of the sad-iron, B the removable cover, C the fuel, D the grate, E the ash-pit, F the ash-pit door, G the chimney, and E the handle, all arranged and operating as usual, except as hereinafter described.

An ash-pit door, F, is made vertically sliding in a recess at the rear end of the body of the sad-iron, so as to be flush therewith on the outside. It has suitable openings, a , controlled by a sliding damper, a' , which, when the ash-pit door is closed, permit the admission of a regulated amount of air. The fire-grate D is raised a small distance above the bottom of the sad-iron, to form a suitable ash-pit, E, which communicates with the opening c at the rear end of the sad-iron, through which the ashes may be removed after the ash-pit door is raised. This fire-grate D is removably supported upon projections b , formed within the body of the sad-iron, and it is provided with suitable perforations to admit air to all parts of the fuel.

The cover B is provided, near its point, with a notch, d , which engages with a projection, e , on the body of the sad-iron, as shown, and within the opposite end of the cover is secured a spring-bolt, f , which engages into a recess, g , in the rear end of the body of the sad-iron, all so arranged that when the bolt is withdrawn

the cover may be removed by lifting up the rear end in advance of the forward end. This construction is of equal advantage in replacing the cover again, which may be done by simply actuating the cover in the proper manner and pressing it to its seat without requiring the operator to touch any part of the body of the sad-iron, thus avoiding all danger of burning.

Increased firmness of the cover upon its seat is obtained by providing the rear end of the cover with a mortise to engage with the tenon h , which latter forms an upward continuation of the rear side of the sad-iron.

The chimney G is secured in the usual manner to the forward end of the cover, and communicates with the interior of the sad-iron to carry off the products of combustion.

i is a diaphragm dividing the chimney, and this diaphragm connects with another diaphragm, j , secured to the cover of the sad-iron, to form two passages, $m n$, one communicating with the forward end and the other with the rear end of the combustion-chamber, and upon the free end of the chimney is removably secured the cap o , provided with a half-circular opening, p . By this means the cap may be turned to have its openings register with either one or the other of the two passages $m n$, or partly with either, thus bringing the combustion under such perfect control of the operator that he can at will increase or diminish the combustion at either end of the sad-iron, as required to obtain the most desirable result.

By closing the passage m the combustion may be increased or entirely sustained at the rear end of the sad-iron, while, on the other hand, where an increased heat is demanded at the front end, the combustion may be accelerated at the front at the expense of the rear.

The diaphragm j forms an effective means for guarding the cover against excessive heat at the point where it may inconvenience the operator.

The handle is formed of a hollow tube, which is held between the ends by standards $r s$, secured to the top of the cover. These standards terminate in circular heads u , which engage into the open ends of the handle, and a bar, v , placed centrally within the handle, con-

ncts the top of the standards, all so arranged that a hollow air-space, *w*, is formed through the interior of the handle, to guard the operator against danger of burning by contact.

5 What I claim as my invention is—

1. The combination, with the combustion-chamber, and a divided escape-flue connected therewith, of a rotatable cap placed over the end of the escape-flue, and having one end 10 partially open and constructed to control the same, substantially as described.

2. In a sad-iron provided with a divided escape-flue, one division communicating with the rear end and the other with the front end of the 15 combustion-chamber, a rotatable and adjustable damper jointly controlling the same, substantially as described.

3. In a sad-iron, a divided escape-flue, one division communicating with the rear end and the other with the front end of the combustion-chamber, in combination with the removable cap *o*, having the semicircular opening *p*, substantially as described. 2c

4. In a sad-iron, the combination of the chimney *G*, having the dividing diaphragm *i*, the 25 cover *B*, having the diaphragm *j*, and the cap *o*, having the semicircular opening *p*, all substantially as described.

RUDOLPH F. KLOPP.
